D18463

UNITED STATES PATENT OFFICE.

LOVETT B. HALE, OF BUFFALO, NEW YORK.

DESIGN FOR A DRESS-MAKING TOOL.

SPECIFICATION forming part of Design No. 18,463, dated July 17, 1888.

Application filed September 21, 1885. Serial No. 177,780. Term of patent 14 years.

To all whom it may concern:

Be it known that I, LOVETT B. HALE, a citizen of the United States, residing at the city of Buffalo, in the county of Erie and State of New York, have invented and produced a new and original Design for a Dress-Making Tool, of which the following is a specification, reference being had to the accompanying drawing, forming part thereof.

The accompanying drawing is a top plan view of my new design, fully illustrating the same.

The leading feature of my design consists in a crescent-like contour with angular indentations or notches in its edge, the outside or convex edge of which is angular and irregular in its contour, as shown in the drawing, in which—

A represents the concave or inside of the

crescent, and B the outside or convex edge of the same. *c*, *d*, and *e* represent the angular notches in the side A, and *f* and *g* represent the notches in the side B, while the angles in the side B are represented by the numerals 1 and 2.

What I claim, therefore, and desire to secure by Letters Patent, is—

In a design for a dress-making tool, a brace crescent-like in contour with angular indentations or notches in its edge and with an outside or convex edge which is angular in its contour, presenting right angle 1, notches *f* and *g*, and obtuse angle 2, substantially as shown.

LOVETT B. HALE.

Witnesses:

CELESTIA C. HALE,
S. J. DOUGLASS.
